JOHN EMIL WILLIAM GREVE, OF CHEMNITZ, GERMANY, ASSIGNOR TO WANDERER-WERKE, VORMALS WINKLHOFER & JAENICKE A. G., OF SCHÖNAU, NEAR CHEMNITZ, GERMANY.

CONTROLLING MECHANISM FOR THE PRINTING-RIBBONS OF COMPUTING-MACHINES.

1,099,124.

Specification of Letters Patent. Patented June 2, 1914.

Application filed December 11, 1913. Serial No. 805,963.

To all whom it may concern:

Be it known that I, JOHN EMIL WILLIAM GREVE, subject of the Emperor of Germany, residing at Chemnitz, Saxony, Germany, have invented certain new and useful Improvements in Controlling Mechanism for the Printing-Ribbons of Computing-Machines, of which the following is a specification.

10 This invention relates to a controlling mechanism for the printing ribbons of computing machines, and relates particularly to a mechanism for governing the action of the ribbon in such a manner that the latter is brought into registration with the printing line when an impression is to be made, but removed therefrom to a position of rest after the printing operation, so that the printed characters will be visible immediately after their impression.

The invention also relates to a mechanism for controlling in simple manner the reciprocation of a multi-color ribbon, which is used, for instance, for printing totals and intermediate totals of a particular computation in a different color from the other sums on the sheet, and contemplates the combination of mechanism whereby, after either one of the color-zones of the ribbon has been brought into the printing line for printing, the ribbon will be properly depressed again below the line. The changing of the color-zones of the ribbon is automatically carried out, according to the present invention, by means of the controlling mechanism of the counting-mechanism, when the machine is set for drawing totals or intermediate totals.

Another feature of the present invention lies in the fact that the ribbon controlling mechanism of the computing machine is adapted to be used either with a fixed paper-support provided with paper in rolls, or it can be employed in a machine which possesses a movable carriage for sheet-paper. In cases where the paper rolls are used, so that the numbers are only printed in vertical columns and the totals are similarly printed, the paper is progressed step-by-step after each impression, and when this is the case, the means for causing the ribbon to be depressed from in front of the line of type can be dispensed with, since the just-written number is made visible through the stepping process mentioned. It is otherwise,

however, when a paper-carriage employing sheet-paper is used, particularly when additions are made transversely thereof and the sum appears at the end of the line. In the latter instance, if the ribbon is not carried into and out of registration with the line of type, the printed matter will not be visible during the use of the machine, until the carriage has traveled far enough to the left for the printed numbers to come from under the ribbon and the ribbon-guide. In order then to make the ribbon controlling mechanism applicable to both uses, the present invention contemplates an arrangement of mechanism by means of which the ribbon guide can be positioned stationarily in registration with the printing line as is desirable when the writing appears on a paper roll. For this purpose, when regular postings are to be printed, the ribbon controlling mechanism is withdrawn from the influence of the controlling mechanism of the counting-devices, and is set in inoperative position. The above-mentioned positioning mechanism can, moreover, be used for raising the red-zone of the ribbon into stationary line with the printing line in case it is desired to prominently display a row of numbers, as by printing them in another color.

It is well-known in the art to raise and lower the ribbon in computing machines for the purpose of making the writing visible and a mechanism is also known in which a ribbon having color-zones is reciprocated in order to print results in a different color from the other writings. In the last mentioned mechanism, however, the writing is not visible and for the purpose of changing the color-zone, the ribbon-rolls are moved laterally.

As opposed to the known mechanisms above-mentioned, the apparatus of the present invention possesses the advantages, that not only is a mechanism provided which effects the movement of the ribbon into and out of the line of type, for the purpose of making the writing visible, but also, a device is provided in a visible-writing machine, by which a color-zone ribbon is reciprocated for the purpose of printing results in a distinguishing color. These two mechanisms, which are coexistent in the machine constructed according to the present invention, are suitably governed by a con-

trolling mechanism, which is arranged on a mechanism for determining the engagement and release of the counting mechanism with its setting devices and which is described in my co-pending application, Serial No. 716,478, filed August 22, 1912. By this means the movement of the ribbon into and out of registration with the type-line and the changing of the color-zones of the ribbon are automatically effected during the actuation of the crank-handle of the machine or by its motor-drive, as the case may be, and furthermore, after a resulting movement of the ribbon for changing the color-zone, the mechanism for raising and lowering the ribbon remains in operation, and, after the following printing of the result in another color, the ribbon returns to its normal position.

In the drawings, which illustrate one form of my invention, is shown the mechanism of the apparatus in its various operative positions.

Figure 1 shows the assembled device in a position of rest, Fig. 2 shows the ribbon in raised position immediately after the printing operation, Fig. 3 likewise shows the ribbon in raised position at an intermediate period, Fig. 4 shows the first elevation of the ribbon, when it is to be brought into position for printing red, and Fig. 5 shows the position of the ribbon with the red-zone illustrated at the position of printing.

Referring more particularly to said drawings, S indicates the paper-roll or the paper-roll guide or carrier, before which is mounted the ribbon 1, which is fed to and from the ribbon-rolls or spools F, only one of which is shown in the drawings, the second spool being hidden from sight in the views shown. In passing from spool to spool the ribbon 1 passes over a bow-like ribbon-guide 2 which is adapted to swing on a shaft 3 carried by the machine. Upon the shaft 3 is mounted an oscillating lever 4, upon whose free end is pivotally mounted a rod 5, whose opposite end is pivotally connected to one arm of a two-armed lever 6 which in turn is suitably mounted on a fixed part of the machine. The free end of said lever 6 carries a roller 7, which coacts with a lever 8, pivotally secured, as by a stub or screw 10 to the control-segment 11 of the counting mechanism hereinbefore referred to. As said counting mechanism and its controlling devices, other than the segment 11 and the roller 13 hereinafter mentioned do not enter further into the present description, they are not illustrated in the drawings. The lever 8 is provided at its free end with a track or slide-way 8^a which is concentric to the axis of rotation of the segment 11, and is further provided on its upper edge and above the element 8^a with the stops 8^b and 8^c. The lever 8 also carries a tongue or projection 9,

which slides in a recess formed in the segment 11 and is adapted to project into the cam-slot 12 of the segment 11 and coöperate with the roller 13. For a better understanding of the invention, it might be stated that the roller 13 is suitably carried by an arm, which is connected to an oscillatory housing for the counting mechanism, so that, when the roller 13 is brought rearwardly through the cam-slot 12 by the mechanism of the machine, the counting-mechanism is placed into operative connection with the setting and actuating devices therefor and is then released therefrom. Upon the segment 11, and operatively adjacent said stops 8^b and 8^c is mounted pawl 15 by means of the stub 14, said pawl 15 standing under the influence of the coil-spring 16. Mounted upon a fixed part of the machine by means of the screws 20 is a plate 19 which carries a stop 18, the latter being adapted to positively coact with the pawl 15, in order to throw the latter out at determined periods, while the lever 8 is adapted to be brought into contact with the pawl 15 by means of a coil-spring 17.

The above mentioned rod 5 is provided with a projection 21 against which a plate or segment 22 (Fig. 1) bears, said plate 22 being adapted to be set by means of a hand-grip 23. A leaf spring 24, suitably mounted in the machine frame, is provided with an elevation which bears in any one of the depressions or stops 25 of the plate 22 for the purpose of holding the latter in its various set positions.

The operation of the apparatus is as follows:—In Fig. 1 the assembled apparatus is shown in its normal position of rest, and the roller 13 has not begun its operation in the cam-slot 12 of the segment 11, this being the position of the parts before the computing machine has been set in operation by means of the usual hand crank. The direction of the forward movement of the crank-handle is shown in the drawings by means of the arrows marked V (Figs. 1, 4 and 5) and the direction of the backward movement of the crank is indicated by the arrows marked R (Figs. 2 and 3). Toward the end of the forward movement of the hand-crank in the machine in which the present invention is installed, the roller 13 enters the cam-slot 12 in a lateral direction, as described in the co-pending application hereinbefore referred to. By entering the slot as stated, near the end of the forward movement of the segment 11, the roller 13 avoids contact with the tongue 9, until the return stroke takes place. As is shown in the drawings, the lever 8 is normally held with its lower step 8^c in engagement with the spring actuated pawl 15, so that during the forward movement from Fig. 1 to the position of Fig. 2, the roller 7 of the two-armed lever 6 engages the slideway or track 18

8^a during the ascent of the lever 8. By this action, and through the medium of the rod 5 and the lever 4, the ribbon guide is raised sufficiently to bring the ribbon into the line 5 of printing. This operation is gone through by the end of the forward movement of the crank, at which time the printing hammers have been released and the impressions made. If the segment 11 now makes the return movement, according to the arrows in Figs. 2 and 3, then the roller 13 will depress the tongue or projection 9, as shown in Fig. 3, whereby the ribbon which in this instant is depressed, because the roller 7 has left the slide-way 8^a, is again elevated. This additional movement is in itself superfluous and is carried out, because, as will later appear, the projection of the tongue 9 into the cam-shaft 12 is necessary. It should be noted that the tongue 9 need not be rigidly secured to the lever 8, but can be slidably held under control of a control-device, so that when the roller 13 runs from one side, as in Fig. 3, over the tongue 9, the latter can give against spring pressure and the lever 8 need not be depressed thereby, while, when the movement is from the other side, as in Fig. 4, the control-device for the tongue will operate to cause the downward movement of the lever 8 with the tongue 9. When the lever 8 is depressed, the pawl 15 snaps into the stop 8^b, in which position it remains until it strikes against the stop 18, when it turns on its pivot 14 and releases the lever 8, so that the latter, under action of the spring 17 is drawn upwardly, until the stop 8^c again strikes against the pawl 15.

When a total or an intermediate-total is to be printed, then the roller 13 enters into engagement with the slot 12 at the beginning of the forward movement of the crank, as described in my application, Serial No. 716,478 hereinbefore referred to, because it is necessary for the counting-mechanism to come into immediate engagement with the setting-gear-segments. If the control-segment 11 is now moved again in the direction of the arrow V, then the roller 13, as shown in Fig. 4, runs from the right over the tongue 9 of the lever 8, whereby the latter is depressed and in its depressed position the pawl 15 engages the upper stop 8^b. With the lever 8 thus set, and through the medium of the lever 6, the roller 7, the rod 5 and the swinging arm or lever 4, the ribbon 1 is elevated to a position where the blue-zone of the ribbon is located before the printing line. If the segment 11 is moved still farther, to the position of Fig. 5, then the roller 7 engages below the slide-way 8^a, and actuates the mechanism so that the red-zone of the ribbon comes before the printing line. This occurs at a time, when the printing hammers are released, so that the printing of the totals and intermediate

totals is done in red. Toward the end of the forward crank movement, the roller 13 passes out of the slot 12. The contact of the pawl 15 with the stop 18, the release of the lever 8 and the additional movement of the ribbon, after it has reached its depressed position, all occur in the same manner as heretofore described.

If it is desired to throw the controlling mechanism for the ribbon out of operation during the writing on roll-paper, so as to leave the latter constantly in position before the printing-line, the hand-grip 23 (Fig. 1) is rotated in a contra-clockwise direction until the segment 22 is held with the spring 24 in engagement with the first stop 25. If it is desired to print wholly in red, then the grip 23 is rotated until the last stop 25 is engaged by the spring 24. By rotation of the segment 22 as above described, the rod 5 is elevated, and thereby the lever 6 and the roller 7 are positioned so that it cannot engage the lever 8, which therefore cannot affect the ribbon-guide, and the writing on roll-paper can be carried out without actuating the ribbon to remove it from the printing-line.

What I claim as my invention is:—

1. In a computing machine, the combination with a controlling means for the counting-mechanism, of a ribbon guide carrying a multi-color ribbon, a control-lever on said controlling means operatively connected to said ribbon guide for moving the latter into the printing-line for each printing operation, means acting on said control-lever to determine the extent of the movement of the ribbon guide, whereby the positioning of the different color-zones before the printing line is determined, and means also carried by said controlling means for holding said controlling lever in said color-zone positions until each printing operation is completed.

2. In a computing mechanism, the combination with a controlling means for the counting mechanism, of a ribbon-guide carrying a multi-color ribbon, means interposed between said counting mechanism controlling means and said ribbon-guide for elevating the ribbon to printing position for each printing operation, means acting on said interposed means to position the latter to elevate the ribbon with a different color-zone before the printing line for printing totals, means to restore the interposed means to normal position after the printing of each total, and means to remove the ribbon guide from the influence of said counting mechanism controlling means and lock the ribbon guide in fixed position before the printing line.

3. In a computing machine, the combination with a control-segment for the counting mechanism, of a ribbon guide carrying a multi-color ribbon, a spring-drawn control

- lever on said control-segment, means actuated by said control-lever for elevating said ribbon-guide to the printing-line for each printing operation, means acting on said 5. control-lever to determine the extent of the elevation of the ribbon guide, whereby the positioning of the different color-zones before the printing line is determined, a spring-actuated member on said control-segment for holding said control-lever in said color-zone positions and a stop for releasing said spring-actuated member to restore the control-lever to normal position after each printing operation.
- 15 4. In a computing machine, the combination with a control-segment for the counting mechanism, of a ribbon guide carrying a

multi-color ribbon, a spring-drawn control lever on said control-segment, lever mechanism connected with said ribbon guide and 20 actuated by said control-lever to raise the ribbon into printing line, means to give a different position to the control-lever, whereby a different color-zone on said ribbon will be presented to the printing line, and means 25 to restore said control lever to normal position after each printing operation.

In testimony whereof I affix my signature in presence of two witnesses.

JOHN EMIL WILLIAM GREVE.
